WINDOW VALANCE

George E. Eckert, Fort Atkinson, Wis., assignor
to Moe Light, Inc., Fort Atkinson, Wis., a cor-
poration of Wisconsin

Application September 15, 1950, Serial No. 12,197

Term of patent 14 years

(Cl. D21—6)

To all whom it may concern:

Be it known that I, George E. Eckert, a citizen of the United States, residing at Fort Atkinson, in the county of Jefferson, State of Wisconsin, have invented a new, original, and ornamental Design for a Window Valance, of which the following is a specification, reference being had to the accompanying drawing, forming part thereof.

Fig. 1 is a view in perspective of a window valance embodying my new design.

Fig. 2 is a plan view of the window valance illustrated in Fig. 1.

Fig. 3 is a view on an enlarged scale taken in section on the line 3—3 of Fig. 2.

Fig. 4 is a view taken in section on the line 4—4 of Fig. 2.

I claim:

The ornamental design for a window valance, as shown.

GEORGE E. ECKERT.
